(57) **CLAIM**

The ornamental design for a light emitting sculpture, as shown and described.

DESCRIPTION

FIG. 1 is a front elevational view of a first embodiment of a light emitting sculpture according to the present invention;

FIG. 2 is a rear elevational view of the first embodiment of the light emitting sculpture;

FIG. 3 is a right side elevational view of the first embodiment of the light emitting sculpture;

FIG. 4 is a left side elevational view of the first embodiment of the light emitting sculpture;

FIG. 5 is a top elevational view of the first embodiment of the light emitting sculpture;

FIG. 6 is a bottom elevational view of the first embodiment of the light emitting sculpture;

FIG. 7 is a front elevational view of a second embodiment of a light emitting sculpture according to the present invention;

FIG. 8 is a rear elevational view of the second embodiment of the light emitting sculpture;

FIG. 9 is a right side elevational view of the second embodiment of the light emitting sculpture;

FIG. 10 is a left side elevational view of the second embodiment of the light emitting sculpture;

FIG. 11 is a top elevational view of the second embodiment of the light emitting sculpture;

FIG. 12 is a bottom elevational view of the second embodiment of the light emitting sculpture;

FIG. 13 is a front elevational view of a third embodiment of a light emitting sculpture according to the present invention;

FIG. 14 is a rear elevational view of the third embodiment of the light emitting sculpture;

FIG. 15 is a right side elevational view of the third embodiment of the light emitting sculpture;

FIG. 16 is a left side elevational view of the third embodiment of the light emitting sculpture;

FIG. 17 is a top elevational view of the third embodiment of the light emitting sculpture; and,

FIG. 18 is a bottom elevational view of the third embodiment of the light emitting sculpture.
